CROSS WINDING FRAME FOR WINDING
STRAND MATERIALS

Walter Siegenthaler, Erlenbach, Switzerland, assignor to the firm Scharer-Nussbaumer & Co., Erlenbach, Switzerland

Application August 8, 1934, Serial No. 739,031
In Switzerland and Great Britain August 21,
1933

5 Claims. (Cl. 242—18)

This invention relates to cross winding frames for winding strand materials such as yarns or threads, having reciprocating thread guides, wherein the number of revolutions of the winding spindle decreases as the diameter of the coil of material at the point of application of the yarn or thread increases, while the ratio of gearing between the winding spindle and the drive of the thread guide remains constant, whereby it is possible to obtain a coil of a regular texture throughout the thickness of the coil.

In known cross winding machines of this general type, the speed of turning of the winding has been governed by the size of the winding by varying the drive ratio of the spindle in accordance with the pivotal position of a spindle carrying arm by causing the spindle to move away from a fixed roller. Such a machine is disclosed in French Patent No. 666,033, dated September 26, 1929. However, the machine according to said patent has the limitation that the speed of turning of the spindle is at all times governed by the largest diameter of the winding, rather than by the diameter at the point on the winding on which the thread is being laid by the thread guide. Such a machine is satisfactory only for the winding of cylindrical bobbins.

According to this invention, a belt which is slung round a driving disc carried by a drive shaft and is passed over a tensioning roller is shifted on the driving disc in the transverse direction thereto by action of the thread guide, for the purpose of varying the angular velocity of the winding spindle as imparted to an adjacent friction disc by friction action of the belt in dependence upon the diameter of the winding at the point thereof where the thread is being laid by the thread guide.

Tests have shown that the driving belt running at the same speed as the driving pulley opposes but very little resistance to being shifted on the driving pulley, so that by shifting it the coil being wound is not affected in the least. At the same time this arrangement permits the use of a driving pulley which is fixed to the driving shaft and which is, therefore, not subjected to wear at the portions with which it bears on the shaft. By this means, the mounting of a plurality of individual machines on a common bed is considerably facilitated and a precise operation of the machine is ensured. Moreover, the invention can be embodied in cross winding frames of usual constructions by merely adding supplementary means to the same.

In the drawing a constructional form of the

invention is illustrated by way of example, only the parts being shown which are necessary to a proper understanding of the invention. In the drawing;

Fig. 1 shows an elevation of the machine, according to the invention, partly in section. 5

Fig. 2 shows a plan view of Fig. 1.

Fig. 3 is a front view of the machine, and

Fig. 4 shows a section on the line IV—IV in Fig. 2. 10

The driving shaft 1 is common to a plurality of winding frames mounted on one and the same machine bed which is indicated in Fig. 1 by its top contour line A, but otherwise not shown. This shaft 1 carries a driving pulley 3 for the friction disc 2 of each winding frame. For transmitting the driving motion of the pulley 3 to the disc 2 disposed at right angles thereto, a belt 4 is provided which is slung round the circumference of the pulley 3 and cooperates with the plane end face of the disc 2 by operative frictional engagement. 15

For the purpose of varying the number of revolutions transmitted from the friction disc 2 to the winding spindle 5, the belt 4 which is free of driving tension is shifted in the axial direction of the pulley 3 on the appropriately widened circumferential surface of said pulley, whereby the radial distance between the belt 4 and the axis of the friction disc 2 and winding spindle 5 is correspondingly changed and thus also the number of revolutions transmitted to the latter is altered. 20

To this end, a tensioning roller 6 is provided, which receives the belt in a circumferential groove, for weighting the belt and thus maintaining it tensioned. This tensioning roller 6 is mounted at the end of a lever 7 which is bent in various ways and which is mounted on a pin 8 between two ears 9 which in turn are secured on a slide 10. The slide 10 is mounted on a rod 12 by means of a slot 11 and slidably engages a stud 14 by means of a slot 13 (Fig. 3). 25

The pin 14 is provided on an arm 15 which is fastened on the corresponding end of the rod 12 which is mounted in lower bearings 12' on the drive box 16. At the other end, the rod 12 is bent laterally to form an arm 12' on which a connecting piece 17 is displaceably arranged and adapted to be held in adjusted position by clamping screw 17', which also serves for pivotally connecting a link 18 to connecting piece 17. Link 18, in turn, is pivotally connected to a connecting piece 19 which is displaceably arranged on an arm 20 and adapted to be held on this arm 30

in adjusted position by clamping screw 19 similarly as the connecting piece 17. The arm 20 is firmly connected to a flap 21 and pivotally arranged together with the latter on a shaft 22. 5 The flap 21 serves for guiding a thread guide 23 during the reciprocating movement of the latter in the longitudinal direction of the winding spindle in a known manner.

The thread guide 23 is turned outwardly in the 10 direction of arrow *a* in Fig. 4 about the shaft 22 together with the flap 21 during the winding operation in accordance with the increase in diameter of the coil being wound with the thread *B*, which is indicated in chain dotted lines in this 15 Figure 4. At the same time the arm 20 is correspondingly rocked in the directions of the arrows *b* in the Figs. 3 and 4, and the arm 12' is also rocked in the direction of arrow *c* in Fig. 3 by means of the link 18, so that the rod 12 is turned about the axis of the same. Consequently, the arm 15 is rocked in the direction of arrow *d* in Fig. 3 accordingly and the slide 10 is shifted, by means of the stud 14, in the direction indicated by the arrow *e* in this figure. 20 25 During this movement the belt 4 is shifted on the circumference of the pulley 3 in the axial direction of the latter by the tensioning roller 6 moving together with the slide 10, so that the belt is gradually approached on the exterior circumference of the friction disc 2 and thus the number of revolutions of this disc is lessened. On the finished coil having been doffed, the winding frame is restored to the previous condition of operation by rocking the thread guide 23 into 30 35 initial position.

Owing to the connecting pieces 17 and 19 being adjustable longitudinally of the respective arms 12' and 20 and accordingly the points at 40 which the link 18 acts on these arms, this arrangement permits of regulating the range of 45 rocking movement of the thread guide 23 and thus the extent of displacement of the belt 4 on the pulley 3.

A longitudinally displaceable rail 24 serves for 45 setting the friction disc 2 into operative position in engagement with the pulley 3. To this end, the rail 24 is displaced so as to swing a lever 26 about a pivot 27 in the direction towards the driving pulley 3. The lever 26 is connected with a 50 dish-shaped disc 30 loosely mounted on the spindle 5 and serving as an abutment for a coil spring 31 surrounding this spindle and bearing with its other end against a central hub member 32. Between the disc 30 and the hub member 32 an intervening sleeve 33 is provided which 55 projects radially so as to overlie the circumferential rim of the disc 30 in a manner to be displaceable relatively thereto. During the swinging movement of the lever 26 referred to above, at first the disc 30 is carried along for conjoint movement, while the spring 31 is compressed, and thereupon the friction disc 2 is pressed against the driving belt 4 for driving engagement therewith. A stop member 34 operable by means of a 60 handle 35 and cooperating with a projection 36 on the outer bearing of the rail 24 serves for arresting this rail in its position corresponding to the relative disposition of the disc 2 and the pulley 3 providing operative frictional engagement between these two parts. 65

I do not limit myself to the particular size, shape, number or arrangement of parts as shown and described, all of which may be varied without going beyond the scope of my invention as shown, 70 described and claimed.

What I claim is:

1. An automatically regulated speed varying drive for cross winding machines having driving shafts and driven winding spindles angularly disposed relative to the drive shafts, and pivotally mounted oscillating thread guides in contact with the winding, said drive comprising a drive disc on the drive shaft, a driven disc on the winding spindle, a tensioning roller, an endless belt passing around the driving disc and between the driving disc and a face of the driven disc and frictionally contacting said face of the driven disc, said belt also passing around said tensioning roller, the portion of said belt passing around said tensioning roller being free of machine driving tension, means connecting the thread guide with the tensioning roller for moving said roller and thereby the endless belt longitudinally of the drive disc and axially of the driven disc in accordance with the pivotal position of the thread guide, 10 to automatically vary the angular velocity of the winding spindle in dependence upon the size of the winding at the point being wound. 15

2. An automatically regulated speed varying drive for cross winding machines having driving shafts and driven winding spindles angularly disposed relative to the drive shafts, and pivotally mounted oscillating thread guides in contact with the winding, said drive comprising a drive disc on the drive shaft, a driven disc on the winding spindle, a tensioning roller, an endless belt passing around the driving disc and between the driving disc and a face of the driven disc and frictionally contacting said face of the driven disc, said belt also passing around said tensioning roller, the portion of said belt passing around said tensioning roller being free of machine driving tension, means connecting the thread guide with the tensioning roller for moving said roller and thereby the endless belt longitudinally of the drive disc and axially of the driven disc in accordance with the pivotal position of the thread guide, 20 to automatically vary the angular velocity of the winding spindle in dependence upon the size of the winding at the point being wound. 25

3. An automatically regulated speed varying drive for cross winding machines having driving shafts and driven winding spindles angularly disposed relative to the drive shafts, and pivotally mounted oscillating thread guides in contact with the winding, said drive comprising a drive disc on the drive shaft, a driven disc on the winding 30 spindle, a tensioning roller, an endless belt passing around the driving disc and between the driving disc and a face of the driven disc and frictionally contacting said face of the driven disc, said belt also passing around said tensioning roller, the portion of said belt passing around said tensioning roller being free of machine driving tension, means connecting the thread guide with the tensioning roller for moving said roller and thereby the endless belt longitudinally of the drive disc and axially of the driven disc in accordance with the pivotal position of the thread guide, 35 to automatically vary the angular velocity of the winding spindle in dependence upon the size of the winding at the point being wound, said connecting means including a slide. 40

3. An automatically regulated speed varying drive for cross winding machines having driving shafts and driven winding spindles angularly disposed relative to the drive shafts, and pivotally mounted oscillating thread guides in contact with the winding, said drive comprising a drive disc on the drive shaft, a driven disc on the winding spindle, a tensioning roller, an endless belt passing around the driving disc and between the driving disc and a face of the driven disc and frictionally contacting said face of the driven disc, said belt also passing around said tensioning roller, the portion of said belt passing around said tensioning roller being free of machine driving tension, means connecting the thread guide with the tensioning roller for moving said roller and thereby the endless belt longitudinally of the drive disc and axially of the driven disc in accordance with the pivotal position of the thread guide, 45 to automatically vary the angular velocity of the winding spindle in dependence upon the size of the winding at the point being wound, said connecting means including a slide and control linkage, said linkage having adjustable means for regulating the leverage of said connecting means for varying the extent of movement of said belt longitudinally of the driving disc. 50

4. An automatically regulated speed varying drive for cross winding machines having driving 55

shafts and driven winding spindles angularly disposed relative to the drive shafts, and pivotally mounted oscillating thread guides in contact with the winding, said drive comprising a drive disc on the drive shaft, a driven disc on the winding spindle, a tensioning roller, an endless belt passing around the driving disc and between the driving disc and a face of the driven disc and frictionally contacting said face of the driven disc, 5 said belt also passing around said tensioning roller, the portion of said belt passing around said tensioning roller being free of machine driving tension, means connecting the thread guide with the tensioning roller for moving said roller and thereby the endless belt longitudinally of the 10 drive disc and axially of the driven disc in accordance with the pivotal position of the thread guide, to automatically vary the angular velocity of the winding spindle in dependence upon the size of the winding at the point being wound, said connecting means including a slide and control linkage, said linkage having adjustable means for regulating the leverage of said connecting means for varying the extent of movement of said belt 15 longitudinally of the driving disc, and a substantially horizontal pivot joint between said slide and said tensioning roller whereby the weight of said roller tensions said belt.

5. An automatically regulated speed varying 20 drive for cross winding machines having driving 30

shafts and driven winding spindles angularly disposed relative to the drive shafts, and pivotally mounted oscillating thread guides in contact with the winding, said drive comprising a drive disc on the drive shaft, a driven disc on the winding 5 spindle, a tensioning roller, an endless belt passing around the driving disc and between the driving disc and a face of the driven disc and frictionally contacting said face of the driven disc, said belt also passing around said tensioning 10 roller, the portion of said belt passing around said tensioning roller being free of machine driving tension, means connecting the thread guide with the tensioning roller for moving said roller and thereby the endless belt longitudinally of the 15 drive disc and axially of the driven disc in accordance with the pivotal position of the thread guide, to automatically vary the angular velocity of the winding spindle in dependence upon the size of the winding at the point being wound, said connecting means including a slide, said tensioning 20 roller being provided with a circumferential groove in which said belt runs and is guided, said roller being pivotally mounted whereby its weight tensions said belt, longitudinal movement of said 25 roller serving to move said belt through lateral pressure on the belt exerted by the wall of the roller groove.

WALTER SIEGENTHALER. 30
